UNITED STATES PATENT OFFICE.

WARREN L. STARKEY, OF PATERSON, NEW JERSEY.

SCHOOL-DESK.

SPECIFICATION forming part of Letters Patent No. 537,081, dated April 9, 1895.

Application filed August 6, 1894. Serial No. 519,547. (No model.)

To all whom it may concern:

Be it known that I, WARREN L. STARKEY, a citizen of the United States, residing in Paterson, county of Passaic, and State of New Jersey, have invented certain new and useful Improvements in Adjustable Hygienic School-Desks; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention is an improved school seat and desk and has special reference to mechanisms for quickly adjusting the seat and desk to the height of the scholars using them.

The invention consists in certain novel features which will be described and claimed.

In the annexed drawings, Figure 1 is a side elevation of a school seat and desk constructed in accordance with my invention. Fig. 2 is a front elevation of the same with a portion of the seat removed. Fig. 3 is a side elevation of one of the standards. Fig. 4 is a side elevation of a part of the device looking at the inner side of the standard. Fig. 5 is a vertical transverse section taken on the central line of Fig. 4 and Fig. 6 is a detail view of a portion of the clamp by which the desk is fastened to the floor.

The standard or leg *a* is provided at its upper end with the central open-ended slot *b* and the narrow beveled open-ended slots *c* on the opposite sides of the said slot *b*. One of the side walls of the open-ended slot *b* is provided with a rack bar *d*, as clearly shown, the purpose of which will hereinafter appear.

40 On the front edge of the leg *I* provide an offset *e* which is constructed with slots *f* *g* and a rack-bar *h* similar in construction to the slots *b* *c* and the rack bar *d*. Below the slots *b* *f* on the side of the standards *I* provide the lugs or stops *i* *j* which are adapted to limit the downward movement of the desk and the seat, as will hereinafter appear.

The desk *k* is provided with the depending arms *l* which pass down on the outer sides of the standards or legs *a* and carry headed studs *m* which engage and slide in the beveled slots

c, thereby guiding the desk in its vertical movements and preventing lateral movement of the same. The two arms *l* are held together by a connecting rod *n* and nuts *o* on the ends of the same. This rod *n* passes through a hollow shaft *p* which is journaled in the arms *l* and projects beyond one of them so as to be engaged by a wrench or crank-arm in the operation of the device. Near the ends of the hollow shaft *I* key thereto the pinions *q* which engage the rack bars *d* as clearly shown so that when the shaft is rotated the pinions will be caused to move over the rack-bars and the desk thereby adjusted vertically. Ratchet wheels or disks *r* are also keyed on the hollow shaft and may be formed integral with the pinion. These ratchet wheels are engaged by balanced pawls *s* which are pivoted on the inner side of the arms *l* and are provided with lugs *t* adapted to impinge against pins *u* on the standards and be thereby automatically disengaged from the ratchet wheels.

The front of the desk forms a part of the back of the seat as shown at *v*. The lower portion of the seat back is formed by slats *w* secured to the upper ends of the sliding plates or standards *x* and the seat proper *y* is composed of slats secured to brackets or arms *z* which are hinged to the sliding plates *x* in the usual manner. The sliding plates *x* are held to the legs or standards *a* by means of headed studs engaging the slots *g* and are held together by means of the slats *w* and a connecting rod *A*, similar to the connecting rod *n*. They are adjusted vertically by means of a hollow shaft *B*, and pinions *C* engaging the rack bars *h*, as will be readily understood. The arms *l* and *x* when in their lowest positions, impinge upon the lugs or stops *i* *j* which serve to prevent the said arms from being lowered to too great an extent. These stops also serve to relieve the strain on the rack bars and pinions when the desk and seat are in their lowest positions. The pinions and ratchet wheels are inclosed by covering or fender *D* to prevent the clothes of the pupil being soiled by the oil, &c.

The legs or standards *a* are provided at their lower ends with the horizontal flanges *E* which are adapted to pass under the brack-

ets F secured to the floor of the school-room and provided with longitudinal slot G in which thumb screws H are mounted, said thumb-screws bearing on the flange E of the 5 legs or standards and thereby securing the desk in position.

The operation of the device is thought to be obvious. When it is desired to raise the seat or the desk the crank handle is engaged 10 over the end of the shaft and then rotated which will cause the pinion to move over the rack-bar and raise the desk or the seat, as the case may be. Should it be desired to lower the desk or the seat it is raised to its fullest 15 extent so as to cause the pawl s to impinge against the top pin u and be thereby disengaged from the ratchet wheel. The reverse movement of the shaft will be permitted and the device can be lowered until the pawl 20 strikes the lowest pin u and is thereby thrown into engagement with the ratchet wheel after which the device is raised to the desired point. It will thus be seen that the desired adjustment can be quickly accomplished without 25 the handling of any part except the operating crank arms.

The manner of clamping the legs to the floor permits the desk to be quickly changed or secured in position and will be found especially advantageous when it is desired to 30 remove a broken desk.

The desk top may be stationary, as indicated, or it may be made to fold over a pocket, as may be preferred, and the adjustment can 35 be affected whether it is occupied or unoccupied and whether folded or open.

The device is very simple in its construction and the desk will weigh but little more than the ordinary non-adjustable desk. At

the same time, it can be quickly adjusted in accordance with hygienic principles.

I do not intend to limit myself to the precise construction shown and described, as various alterations can be made without departing from the scope of my invention.

Having thus described my invention, what I claim as new, and desire to secure by Letters Patent, is—

In an adjustable desk, the combination with the legs or standards each being provided with two vertical open ended slots and with a centrally arranged vertical open ended slot having one of its sides provided with a rack-bar, of the desk proper, arms depending vertically from the desk and arranged outside of the legs or standards, a series of headed pins projecting inward from said arms and adapted to slide in the open ended slots of the legs, a hollow shaft journaled in said arms, a pinion secured at each end of the shaft and adapted to engage the rack bar, a ratchet fixed on said shaft, a pawl engaging said ratchet and pivotally secured to the depending arm of the desk, said pawl being provided with a projection, and a series of two pins secured to the legs or standards in the path of the ratchet and adapted to operate the pawl when the desk is raised or lowered to its highest or lowest position respectively, all said parts substantially as described.

In testimony that I claim the foregoing I have hereunto set my hand this 28th day of July, 1894.

W. L. STARKEY.
